UNITED STATES PATENT OFFICE.

HENRY W. DEMING, OF WATERBURY, CONNECTICUT, ASSIGNOR OF ONE-HALF TO SAMUEL P. WILLIAMS, OF SAME PLACE.

PAPER BOX.

SPECIFICATION forming part of Letters Patent No. 415,858, dated November 26, 1889.

Application filed July 22, 1889. Serial No. 318,301. (No model.)

To all whom it may concern:

Be it known that I, HENRY W. DEMING, a citizen of the United States, and a resident of Waterbury, New Haven county, Connecticut, have invented certain new and useful Improvements in Paper Boxes, of which the following is a specification.

My invention is a knockdown box consisting of a blank formed so as to be folded in its corners when the edges are turned up to form the sides and provided with fastening devices, as fully set forth hereinafter, and as illustrated in the accompanying drawings, in which—

Figure 1 is a perspective view illustrating a portion of a blank as partly folded to form my improved box. Fig. 2 is a perspective view illustrating the position of parts at one corner before the sides are brought to their final positions. Fig. 3 is a perspective view of one corner of the completed box. Fig. 4 is a view illustrating a different form of securing device from that shown in the other figures. Fig. 5 is a plan of a portion of the blank, and Fig. 6 is a plan of a portion of the blank with one of the ends folded over onto the body of the blank and triangular sections thereof pasted to the underlying portions.

The box is made from an oblong or rectangular strip of paper or board A, which is scored or creased along lines 1, parallel to the edges and extending the whole length and width of the strip, and also on diagonal lines 2, extending diagonally each from one of the corners of the blank to the point x, where the adjacent lines 1 1 intersect. The extreme corners may be cut off on the line v, Fig. 5. The blank thus formed may be bent or folded upon the lines 1 1 to form upturned side and end flanges a b, and upon the line 2 as well as upon the extensions of the lines 1 1 beyond the intersecting points x to form at each corner a fold y, Fig. 2, which may be turned against either of the sides a b.

To a face of a triangular section, as s t x, of the fold I preferably apply cement of suitable character, (indicated by the shaded portion, Fig. 5,) so that when the end portion of the blank is folded over upon the body of the same a triangular section (indicated by the shaded portion of Fig. 6) will consist of two thicknesses cemented together, so that when

the side b, which is folded over onto the body of the blank, is raised and turned outward, as in Figs. 1 and 2, the side a will also be raised and turned inward, and the triangular connecting portion 5, Figs. 1, 2, and 6, will swing naturally, without any manipulation, into position against the face of the thickened or cemented portion.

By cementing one section down upon the face of the body of the box, as above described, I not only secure the ready and automatic adjustment of the parts as the side a is turned up and the side b is turned out, but I also greatly stiffen the corners of the sides which are exposed, so as to add materially to the strength of the box. The increased strength of these portions of the box is also of great advantage, in order to secure a firm attachment of securing devices of any desired character, by means of which the parts are held in position when folded up to a box form.

The securing devices may be attached to or form part of the strengthening corners or side of the box. Thus in Fig. 4 the doubled or thickened corner is shown as cut away to form a lip 6, which may be introduced into a slot 7 in the triangular section 5 of the box, so as to hold the parts temporarily in place. I prefer, however, to make use of a permanent attaching device, which may be of different forms, capable of being manipulated to secure the parts in place when the sides are turned up into position. Thus, as shown in full lines in Fig. 2, I cement between the two connected portions or sections at the ends of the sides gummed strips e, which extend beyond the edges of the box and do not interfere in any way with the knocking down of the blank; but when the box is set up each strip e may be moistened and folded down against the inside of the adjacent section 5, to thereby hold the latter firmly in position and maintain the box shape of the structure.

Instead of cementing the gummed strips e between the two connected portions, as just described, they may be secured to the outer face of the side against which the fold y is laid, as shown in Fig. 1, and when the box is set up folded against the sections 5; or they may be secured to the sections 5 and folded over the side of the box against which it is

laid, as shown in Fig. 3. The gummed strips *e* need not project beyond the edges of the blank, but may be arranged as illustrated in dotted lines in Figs. 1, 2, and 5, in which case they are secured either to the side *a* or the triangular portion *s t x*, so as to lie between them when they are folded against each other, as shown in Fig. 2, and are adapted to be folded over the flaps *5* and hold them against the sides of the box. By these means I construct a blank capable of being transported in a flat state, and can yet transform the blank readily into a permanent box. Under some circumstances the folds *y* need not be cemented to the sides of the box against which they are laid, the fastening devices, as the strips *e*, being relied upon to hold the parts together. This is particularly the case when the strips are arranged as indicated by the dotted lines; but a box thus constructed will lack the rigidity which is imparted by gumming the corner sections to the sides, as before described.

The cover of a box constructed according to my invention may be made in the same way as is the box itself, or in any other desired manner. The folds *y* may be turned down against the outer sides of the side pieces of the one; and it will be evident that the gummed strips may be used whenever it is necessary to secure together the sides and corner-pieces of any desired construction, whether in the form of folds or flaps or tongues.

Without limiting myself to the precise construction and arrangement of parts shown, I claim—

1. A knockdown-box blank constructed to be folded along the lines 1 and 2 to form upturned ends and sides and folds at the corners, and provided with fastening devices consisting of gummed strips secured to the blank and having free gummed ends for securing the corner folds when the box is set up, substantially as set forth.

2. The combination, with the inturned ends of the blank, one section cemented upon the other, of a fastening device secured between the adjacent cemented faces and extending so as to be turned over and secured to the other section, substantially as set forth.

3. The combination, with the blank having corner folds, of strips *e*, secured each to one side section of the blank adjacent to the corner in position to be folded over and secured to the corner fold, substantially as set forth.

4. The combination, with the blank having folded corner sections, of gummed strips secured to a portion of the blank adjacent to each section, for the purpose specified.

In testimony whereof I have signed my name to this specification in the presence of two subscribing witnesses.

HENRY W. DEMING.
